UNITED STATES PATENT OFFICE.

JAMES D. NELSON, OF CINCINNATI, OHIO.

ELECTRIC SIGNAL SYSTEM.

1,266,144.

Specification of Letters Patent. Patented May 14, 1918.

Application filed May 5, 1917. Serial No. 166,588.

To all whom it may concern:

Be it known that I, JAMES D. NELSON, a citizen of the United States of America, and resident of Cincinnati, in the county of 5 Hamilton and State of Ohio, have invented a new and useful Improvement in Electric Signal Systems, of which the following is a specification:

Electric signal systems now in use for 10 giving signals for indicating a flow of water through automatic fire extinguisher systems, are so equipped that the elements of the apparatus which form parts of these systems, involve the loss of water through 15 bleeder passages and similar arrangements, as well as necessitating the use of diaphragms which in time crack and necessitate repairs at inconvenient times.

An object of my invention is to produce 20 an electric signal system in which the flow of water into special alarm devices is eliminated and in which buckling diaphragms and similar constructions are avoided.

A further object is to produce an improved 25 electric signal system in which the parts susceptible to disarrangement are accessible without having to disturb any portion of the fire extinguisher system with which my improved electric signal system 30 may be associated, such as shutting off water or air pressure, draining the system or even destroying pipe and other connections in order to reach the required elements for 35 repairs or replacement. These and other objects are attained in the system described in the following specification and illustrated in the accompanying drawings, in which:

Figure 1 is a somewhat diagrammatic 40 view of my improved system, certain elements being shown in sectional elevation for convenience of illustration.

Fig. 2 is a diagrammatic view of the arrangement of certain of the elements of the 45 system and the positions they occupy at different periods of the operation thereof.

Fig. 3 is a fragmental sectional view taken on the line 3—3 of Fig. 1.

Fig. 4 is a perspective view of a fragment 50 of one element of my improved system, certain parts being shown broken away for convenience of illustration.

My improved system consists of an element 5 located in a casing 6 which is connected with the sprinkler system 7 by means 55 of a pipe nipple 8, element 5 being opera-

tively connected with a flow responsive valve 9 located in the fire extinguisher system for the purpose of operating to send in a signal instantly upon operation of valve 9. A bar 10 pivotally mounted at a point 11 in pipe nipple 8, is the operative connection between elements 5 and valve 9. Valve 9 is provided with a finger 12 which bears upon end 13 of lever 10 and causes its opposite end 14 to be raised when the valve is closed and to be lowered when the valve is opened. Element 5 consists of a pair of magnets 15 and 16 having their pole ends spaced apart and connected by a frame 17 consisting of a bar 18 extending transversely of magnet 15, a bar 19 extending transversely of magnet 16, and rods 20 and 21 connecting the ends of bars 18 and 19. Magnets 15 and 16 are so located with relation to one another that the north pole of magnet 15 and the south pole of magnet 16 are located substantially over one another with the south pole of magnet 15 located over the north pole of magnet 16. Both magnets 15 and 16 are preferably of the permanent type. Between rods 20 and 21 a housing 22 is located. This housing extends from one side wall 23 of casing 6 to the opposite side wall 24 thereof, thus passing between magnets 15 and 16. The distance between the pole ends of magnets 15 and 16 is sufficient to permit magnet 16 to engage the under side of housing 22 when magnet 15 occupies an elevated position with relation thereto, magnet 16 thereby being permitted to occupy a position in spaced relation to housing 22 when magnet 15 engages the upper side of the housing. Thus when arm 10, which is connected with magnet 15 at a point 25, is in its normal position as disclosed in Fig. 1, magnet 16 is in engagement with the under side of the housing and magnet 15 is in an elevated position with relation thereto. Within housing 22 is a swinging needle 26 which is pivotally mounted at a point 27 in the top and bottom of the interior of the housing so as to swing freely therein. This needle 26 is one of the permanent magnet type and has extending from the under side of its north end a pin 28. At the side of housing 22 adjacent to the south pole of magnet 15 and the north pole of magnet 16 is a delicate contact switch 29. Pin 28 of swinging magnet 26 is so positioned as to engage finger 30 of switch 29 to close the switch when the magnet is swung upon its pivot 27. Under

normal conditions, when magnet 16 occupies a position in contact with the under side of housing 22, the north end of magnet 26 registers with the south end of magnet 16, but 5 when frame 17 is lowered to withdraw magnet 16 and to place magnet 15 in engagement with housing 22, the physical position which swinging magnet 26 occupied up to this operation will now be reversed so as 10 to bring its south end into register with the north end of magnet 15 and its north end into register with the south end of magnet 15, thereby bringing pin 28 into engagement with switch 30 to close the switch. In 15 the construction of the apparatus thus for described I preferably construct arm 10, nipple 8, casing 6, frame 17, and housing 22 of non magnetic material such as brass. This is for the purpose of rendering the 20 swinging of magnet 26 in response to the movement of the magnets 15 and 16, free from magnetic disturbances other than those produced by magnets 15 and 16.

For the purpose of enabling magnets 15 25 and 16 to approach swinging magnet 26 more closely and to thereby affect its swinging movement more strongly, I have decreased the thickness of the top and the bottom of housing 22 at the points the ends of 30 magnets 15 and 16 engage. This produces thin walls in the housing and does not materially weaken the strength thereof.

The remainder of the system is illustrated 35 diagrammatically and is of the closed circuit type. In the elements comprising this portion of the system I have disclosed a magnet 31 which is in closed circuit with a battery 32 and which controls an arm 33 pivotally mounted at a point 34. At one end 40 of arm 33 a rack 35 is formed for coöperation with a pinion 36 of a retarding mechanism 37 and at the opposite end of arm 33 a finger 38 of an arm 39 is engaged for releasing a signal transmitter 40 by disengaging a 45 pawl 41 therefrom. Transmitter 40 coöperates with a signal transmitting key or switch 42 which is connected with circuit 43 adapted to transmit signals to a signal recorder 44 located at the central office. Under 50 normal conditions arm 33 is elevated by magnet 31 to permit detent 41 to lock transmitter 40 against operation, but when magnet 31 is deenergized, arm 33 is released and detent 41 unlocks the transmitter 40 for the 55 transmission of a signal to signal recorder 44. Switch 29 is connected with battery 32 by means of leads 45 and 46 which are in turn connected with main line leads 47 and 48 respectively and are adapted to short circuit these leads when switch 29 is closed.

In describing the operation of my improved system, the parts will be considered to be in their normal positions as disclosed in Fig. 1, and as shown in full lines in Fig. 65 2, the positions of magnets 26 and 15 when

magnet 15 is lowered to swing magnet 26, being shown in dotted lines in Fig. 2. It will be assumed that a flow of water through the fire extinguisher system 7 takes place to raise valve 9. Immediately upon the raising 70 of valve 9, lever 10 will operate to drop frame 17 and its magnets 15 and 16. Swinging magnet 26, which in its normal condition occupies the position disclosed in Fig. 1 and in full lines in Figs. 2 and 3, will be 75 acted upon by magnet 15 according to the magnetic law of "like poles repelling and unlike poles attracting", to cause it to swing to the position disclosed in dotted lines in Fig. 2, in which its pin 28 has been brought 80 into engagement with finger 30 of switch 29 to short circuit battery 32. Thus upon the short circuiting of battery 32 by the closing of switch 29, magnet 31 is deenergized to allow arm 33 to drop and to operate retard 85 mechanism 37 for the purpose of releasing transmitter 40 for the purpose of transmitting a signal from transmitter 40 to signal recorder 44. However, should the flow of water through extinguisher system 7 be for 90 less than a predetermined time, valve 9 will operate to cause magnet 26 to swing to open the switch 29 and thereby reënergize magnet 31 to again attract the member 33 of the retarding mechanism, before the retarding 95 mechanism has had time to release transmitter 40 for signal operation.

Having thus described my invention, what I claim is:

1. An electric signal system comprising a 100 casing having its interior communicating with a fire extinguisher system to be supervised, a valve in said extinguisher system, a magnet located in the casing, means operatively connecting the magnet and the valve, 105 and a signaling device located adjacent to the magnet and outside the walls of the casing, adapted to send a signal when the valve is operated to cause said magnet to exert its influence upon the signaling device. 110

2. An electric signal system comprising a casing having its interior communicating with a fire extinguisher system to be supervised, a valve located in the extinguisher system, a magnet located in the casing, 115 means operatively connecting the valve and the magnet, whereby movement of the valve will reciprocate the magnet within the casing, and a magnetically controlled signal sending switch located exteriorly of the casing, adjacent to the magnet, and adapted to close a signal sending circuit when the magnet is moved in one direction in response to opening movement of the valve and to break the signal sending circuit when the magnet 120 is moved in the opposite direction in response to closing movement of the valve.

3. An electric signal system comprising a casing having its interior communicating with a fire extinguisher system to be super- 130

vised, a valve located in the fire extinguisher system, a magnetically controlled signal sending device located adjacent to the casing and exteriorly thereof, a magnet located within the casing adapted to initiate signal sending operation of the signal sending device when moved toward said device, a second magnet located within the casing adapted to control the signal sending device to stop signal transmitting operation of the device, and means operatively connecting the magnets and the valve, whereby the opening and closing movements of the valve in response to changes of conditions within the extinguisher system, will reciprocate the magnets to control operation of the signal sending device.

4. An electric signal system comprising a valve located in a fire extinguisher system to be supervised, a signal transmitter, a timing device adapted to control the operation of the transmitter, and a magnetic device located within the extinguisher system and operatively connected with the valve and the timing device, whereby said timing device will be controlled to operate the transmitter in response to a change from the normal condition of the valve for a predetermined time.

5. An electric signal system comprising a valve located in a fire extinguisher system to be supervised, a signal transmitter, a timing device responsive to an abnormal condition of the valve for a predetermined time to trip the transmitter, and a magnet located in the fire extinguisher system and operatively connected with the valve, adapted to control operation of the timing device, whereby movement of the valve in response to a change of conditions within the system, will affect the operation of the timing device.

6. An electric signal system comprising a valve located within an automatic fire extinguisher system to be supervised, a non magnetic casing having its interior communicating with the interior of the extinguisher system, a magnet located within the casing and operatively connected with the valve, and a signal transmitting device

adapted to be controlled by operation of the magnet in response to movement of the valve, whereby signals will be transmitted upon changes in conditions within the fire extinguisher system.

7. An electric signal system comprising a valve located within an automatic fire extinguisher system to be supervised, a non magnetic casing connected with the extinguisher system and having its interior communicating with the interior of the extinguisher system, a magnet located within the casing, an arm operatively connecting the valve and the magnet, a magnetically responsive member located exteriorly of the casing and adapted to be operated in response to operation of the magnet, and a signal transmitter operatively connected with the magnetically responsive member, operated in response to a change in the conditions in the system.

8. An electric signal system comprising a valve located within a fire extinguisher system to be supervised, a non magnetic casing connected with the fire extinguisher system and having its interior communicating with the interior of the system, a magnet located within the casing, an arm operatively connecting the valve and the magnet, a magnetically responsive member located exteriorly of the casing and adapted to be operated in response to operation of the magnet within the casing, a timing device responsive to operation of the magnetically controlled member, and a transmitter operatively connected with the timing device and adapted to be operated upon operation of the timing device in response to operative movement of the magnet upon actuation of the valve in response to a change of conditions in the extinguisher system for a predetermined time.

In testimony whereof, I have hereunto subscribed my name this 2nd day of May, 1917.
